BILLET CENTERING APPARATUS

Raymond E. Dewey, Shelby, Ohio, assignor to
The Ohio Seamless Tube Company, Shelby,
Ohio, a corporation of Ohio

Application June 21, 1941, Serial No. 399,167

9 Claims. (Cl. 78—96)

This application relates to a billet centering apparatus, and more particularly, to an improved arrangement of apparatus for forming an opening in a billet centrally of an end thereof prior to forming the billet into a seamless tube.

Billets which are to be formed into seamless tubes on a piercing mill are cylindrical in shape and it is desirable that the billet be formed with an opening centrally of an end thereof prior to being taken to the piercing mill. In order that the material of the billet will be distributed uniformly about the piercing point of the piercing mill, it will be apparent that such opening must be accurately located centrally the billet end.

One of the difficulties encountered in practice, aside from variations in billet diameter, is the considerable variation in the length of the billets that require to be handled in such centering operation, for example from 15 inches to 9 feet. Thus a pusher type feed, such as an air-actuated plunger involves the use of accessory parts, with frequent changes, to accommodate such different length of billets. Also the billets are not always straight as they come from the heating furnace, particularly in the case of longer billets, and if such a bowed billet is supported against longitudinal movement from its rear end, it becomes difficult properly to center the opening in its front end.

One of the principal objects of this invention is to provide an apparatus for forming an opening in the end of a heated billet which may be employed readily in connection with a part of the conveyor system used to deliver the billet from the heating furnace to the piercing mill. Such conveyor, it will be seen, automatically and without adjustment, can handle a billet of any length within the maximum length.

A further object of this invention is to provide in apparatus of the character referred to, clamping means for engagement with the forward end of a billet which is arranged with respect to a part of a conveyor system so that a billet thereon will be disposed endwise with respect to the clamping means, together with mechanism for forming an opening in the end of the billet while held by the clamping means. By clamping and holding the billet thus at its forward end, the centering of the opening is unaffected by any bowing or crookedness in the body of the billet.

A further object is to provide a novel clamping device, engageable with an end of a billet supported on a part of a conveyor system, which is operable to move the billet to a predetermined position with respect to its conveyor support upon movement of the clamping device into clamping engagement with the billet.

A further object is to provide in apparatus of the character referred to, a device for forming an opening in the end of a billet together with

operating means therefor which is responsive to the operating means for the clamping device employed to hold the billet during the formation of the opening.

5 Other objects and advantages of the invention will become apparent during the course of the following description.

To the accomplishment of the foregoing and related ends, said invention then comprises the 10 features hereinafter fully described and particularly pointed out in the claims, the following description and the annexed drawings setting forth in detail certain illustrative embodiments of the invention, these being indicative, however, of but 15 a few of the various ways in which the principle of the invention may be employed.

In said annexed drawings:

Fig. 1 is a perspective view illustrating the apparatus constructed in accordance with the principles of this invention;

20 Fig. 2 is a vertical sectional view taken substantially on the line 2—2 of Fig. 1;

Fig. 3 is an enlarged vertical sectional view of the pneumatic air hammer as shown in elevation in Fig. 2; and

25 Fig. 4 is a vertical sectional view of the billet clamping device and operating means therefor.

Referring to Fig. 1 of the drawings, the letter A designates, as a whole, a part of a conveyor system adapted to deliver a heated billet endwise to a clamping device indicated, as a whole, by the letter B. The clamping device B is adapted to clamp the end of the billet in which the opening is to be formed and is operable to move the billet into a predetermined position with respect to the conveyor part A. A device C is employed in connection with the clamping device B for forming an opening in the end of the billet while it is held by the clamp B in a predetermined position on the part A.

30 The conveyor support or part A comprises spaced parallel side flanges 1 rotatably carrying a plurality of conveyor rollers 2. The flanges 1 are carried by supporting members 3 and 4. One or more of the rollers 2 are preferably power-driven by a chain 5 operated by an electric motor 6. The end 7 of the part A is arranged adjacent the discharge opening 8 of a furnace, a part 9 of the heating furnace being shown in Fig. 2. The 35 heated billets are forced endwise out of the furnace 9 through the opening 8 onto the supporting rollers 2 of the conveyor part A. After delivery of the billet onto the supporting rollers 2, the supporting rollers 2 driven from the motor 6 will 40 be operative to move the billet into engagement with an abutment 10 for a purpose to be described. After the clamping device B has operated to clamp the billet, and the device C has operated to form an opening in the end thereof, the clamp B is operated to release the billet which

is then picked up by members 11 which are operated to remove the billet transversely from the surface of the rollers 2 onto skids (not shown) or other suitable supporting mechanism for transmission to the piercing mill. The operating means for the members 11 forms no part per se of this invention, and accordingly has not been illustrated. The members 11 merely form a part of the conveying system which is employed to transmit the billet from the heating furnace 8 to the piercing mill.

The construction of the clamping device B is best shown in Fig. 4. In this showing, the clamping device comprises oppositely disposed parts 12 and 13 mounted for sliding movement transversely with respect to the conveyor part A on ways 14 and 15 mounted between spaced vertical supporting plates 16. Each of the parts 12 and 13 is provided with a removable billet engaging clamping member 17. The surface engaging parts 18 of the clamping members 17 are shaped to correspond to the contour of the billet, and upon movement into clamping engagement with the billet, are operable to cover approximately 90 per cent of the circumference of the billet.

Each of the parts 12 and 13 is pivotally connected to a link 19, which in turn is pivotally connected to an end of a lever 20 rotatably mounted on a pin 21 extending transversely of and carried by the plates 16. The other ends of the like levers 20 are each pivotally connected to a link 22, which in turn is pivotally connected to an end of a lever 23 rotatably mounted on a pin 24 extending transversely of and carried by the plate 16. Rotation is imparted to the operating lever 23 through a rocker arm 25 connected thereto. The rocker arm 25 is pivotally connected to a piston rod 26 which is operated by an air cylinder 27 pivotally carried by a trunnion support 28.

The pivotal connection of the piston rod 26 to the rocker member 25 and the trunnion support 28 for the cylinder 27 cooperate in enabling a rocking movement to be imparted to the arm 25 upon operation of the piston 26 by the cylinder 27. Upon operation of the cylinder 27 to move the piston rod 26 outwardly, the operating lever 23 will be rotated in a counter-clockwise direction, and through the links 22, the operating lever 23 will be effective to rotate the levers 20 in opposite directions to move the parts 12 and 13 toward each other and to move the clamping members 17 into clamping engagement with an end of a billet positioned therebetween. By reason of the arrangement of the operating parts for the clamping members 17, the amount of movement imparted to each of the clamping members will be equal. In this manner, the clamping members 17 will be operative to move the billet to a predetermined position with respect to the conveyor support A and with the axis of the billet lying in a vertical plane, indicated diagrammatically by the center line 29, containing the axis of the pin 24.

The clamping surfaces 18 of the clamping members 17 cooperate in aligning the axis of the billet in the plane 29. By reason of the fact that the clamping surfaces 18 cover 90 per cent of the circumference of the billet, the members 17 are operable to compensate for any irregularities in the surface of the billet while permitting sufficient play to insure movement of the members 17 into clamping engagement.

As best shown in Fig. 3, a punch 30 is provided for forming the opening in the end of the billet

held by the clamp B. The punch 30 is mounted for axial movement through a suitable opening formed in the abutment 19, and has its axis positioned in the vertical plane 29 containing the axis of the billet and the pin 24. A connecting member 31 is provided for connecting the punch 30 to the piston rod 32 of a pneumatic air hammer. The air hammer comprises a cylinder 33 in which is mounted a piston 34 for imparting movement to the piston rod 32. Suitable valve mechanism 35 is provided for controlling the admission of air to the cylinder 33 from an air line 36. The air hammer including the cylinder 33 and the valve 35 is a conventional type forming no part per se of this invention. It will be sufficient to point out that the valve 35 is provided with a piston control member 37 adapted to alternately connect the ends of the cylinder 33 with the line 36.

Working strokes will be imparted to the punch 30 as long as pressure is admitted through the line 36, and six working strokes of the hammer will usually be found sufficient to form the desired opening in the end of the billet.

Referring to Fig. 1, there is shown diagrammatically the arrangement of apparatus for controlling the operation of the air cylinder 27 and the operation of the hammer 33. In this showing, a valve 45 is provided for controlling the admission of air under pressure to lines 46 and 47 from a suitable source of air under high pressure (not shown). The valve 45 may be of any conventional type readily purchaseable on the market for alternately connecting one of the lines 46 and 47 to the source of air pressure and the other of the lines to the atmosphere.

The line 47 is connected to one end of the cylinder 27, and upon admission of air under pressure thereto, will be effective to move the piston 26 outwardly as viewed in Fig. 4 to move the clamping members 17 into clamping engagement with an end of a billet. The line 36 for operating the air hammer is shown in Fig. 1 connected to the line 47. A relief valve 48 is provided in the line 36 for preventing operation of the hammer 33 by the admission of air pressure thereto under certain conditions. The relief valve 48 is of a type adapted to alternately connect the line 36 with the line 47 and with the atmosphere, and is provided with a predetermined bias maintaining the valve in a position disconnecting the line 47 from the hammer 33. Upon admission of air to the line 47, the pressure therein will not build up until the clamping members 17 have been moved into clamping engagement with the billet. Upon the building up of pressure within the cylinder 27, such pressure will operate to move the valve 48 against its bias to connect the cylinder 33 to the source of pressure, and the punch 30 will be operated as described above.

The bias of the valve 48 will be so regulated that air will not be admitted to the cylinder 33 until the pressure within the cylinder 27 is sufficient to operatively hold the billet in position through the clamping members 17 to prevent the punch 30 from imparting movement to the billet. The valve 48 is of a conventional construction readily purchaseable on the market, and accordingly has not been illustrated in detail. The arrangement of the valve 48 and the line 36 with respect to the line 47 prevents an untimely operation of the cylinder 33, and makes operation of the cylinder 33 responsive to operation of the cylinder 27. In this manner, the punch 30 will not be operated prior to movement

of the clamping members 17 into clamping engagement with the billet.

After the punch 30 has operated to form an opening in the end of the billet, the valve 45 is operated to connect the line 48 with a source of air pressure to admit air to the other end of the cylinder 27 and to connect the line 47 to the atmosphere. Upon connection of the line 47 to the atmosphere, the valve 48 will operate to connect the line 38 to the atmosphere and release the pressure within the cylinder 33. Immediately upon release of the pressure within the cylinder 33, the spring 49 will be operative to withdraw the plunger 30 to the position shown in Fig. 3. The withdrawal of the punch 30 in this manner enables the members 11 to be operated immediately to lift the billet out of engagement with the rollers 2 and onto skids or other suitable conveying mechanism for transmission to the piercing mill. It will be apparent that if the punch 30 were left in the opening formed in the end of the billet, damage would be caused to the end of the billet upon operation of the lifting members 11.

It will be recalled that the clamping members 17 are operable to move the billet to a position with its axis lying in a plane containing the axis of the punch 30. The clamping members or jaws 17 are also removably secured to the parts 12 and 13 in order that members having different shaped clamping surfaces 18 may be inserted for engagement with billets of various sizes. Since the level, at which a billet of any size will be supported, is fixed by the top supporting surfaces of the rollers 2, it will be apparent that the lower edges 50 of the clamping surfaces 18 will occupy substantially the same position regardless of the size of billet to be clamped. This will be understood by reference to Fig. 4 wherein the dotted lines 18a indicate the position of the clamping surfaces 18 for a smaller size billet. Although the parts 12 and 13 through the clamping members 17 will be operative to align the axis of the billet with respect to the vertical plane 29, it will be apparent that the punch 30 must be adjusted in a vertical plane according to the size of billet being operated upon.

The mechanism for imparting vertical adjustment to the punch 30 is best shown in Fig. 2. In this showing, the punch operating mechanism C is mounted on a support 51 mounted for vertical movement with respect to a support 52 rigidly secured to the foundation structure 53. The support 51 is provided with parts 54 mounted for vertical movement in guide slots 55 formed in the stationary support 52. The parts 54 and 55 guide the vertical movement of the support 51 and prevent horizontal movement thereof. The support 51 is provided with inclined surfaces 56 slidably engageable with members 57 carried by an actuating member 58 mounted for horizontal sliding movement on the support 52. In this manner, the members 57 are, in effect, camming members operable to impart vertical movement to the support 51 and punch operating mechanism C upon horizontal movement being imparted to the support 58.

A manually operable device 59 is rotatably carried by the stationary support 52 and has a threaded shaft 60 engageable with a part 61 integral with the movable support 58 for imparting a controlled movement to the support 58. Upon a change of clamping members 17, the device 59 will be operated to adjust the punch 30 in a vertical plane to align the axis thereof with

the axis of the billet carried by the conveyor support A.

The operation of the apparatus will be apparent from the foregoing, and it will be sufficient to point out that a billet delivered from the furnace 8 onto the rollers 2 will be carried by the power-driven rollers into engagement with the abutment 10. Upon movement of the billet into engagement with the abutment 10, the valve 45 may be operated to admit air to the cylinder 27 for moving the clamping members into clamping engagement with the end of the billet. Such engagement, as pointed out, is effective to align the billet in a predetermined position with respect to the conveyor support A and the punch 30. As the members 17 move into clamping engagement, the valve 48 will automatically function to start operation of the hammer 33 to cause the punch 30 to form an opening in the end of the heated billet. After the opening is formed, the valve 45 will be operated to move the clamping members 17 out of engagement with the end of the billet and to stop operation of the hammer 33 permitting withdrawal of the punch 30 by the spring 49. The members 11 may then be operated by mechanism (not shown) through a control 62 therefor adjacent the control 45 shown in Fig. 1 to remove the billet from the rollers 2 for continuing its conveyance from the furnace to the piercing mill.

From the foregoing it will be apparent that there is provided apparatus which is operable to form an opening centrally of an end of a heated billet in an extremely short period of time at a minimum of expense. It is merely necessary to install the clamping device B and punching mechanism C in such a position that the conveyor mechanism employed for conveying a heated billet from a furnace to the piercing mill will deliver the billet endwise to the clamp B at a point during transit of the billet to the piercing mill. After installation it will be apparent that about the only additional cost of operation involved will be the air necessary to operate the fluid pressure cylinders 27 and 33. The controls for these cylinders may be actuated by the same operator controlling the discharge of the billets from the furnace for transmission to the piercing mill and this may be done in such manner as to not interfere substantially with the continuous flow of billets to the piercing mill.

The adjustments necessary to adapt the apparatus for use with different size billets are extremely simple. In the event that the size of the billets is changed, it is merely necessary to remove the clamping members 17 and insert other such clamping members having clamping surfaces 18 corresponding to the new size of billet, and to operate the manual control 59 to adjust the vertical position of the punch 30 so that its axis will be positioned in a horizontal plane containing the axis of the billet as it rests on the rollers 2.

It will be particularly noted that the conveyor part A cooperates with the clamping member B and punching mechanism C in that it supports the billet at a predetermined level during the punching operation and is operable to deliver a billet endwise into engagement with the abutment 10 intermediate the clamping jaws 17. The clamping mechanism B cooperates with the parts A and C in that it aligns the position of the billet in a vertical plane with respect to the conveyor A for operation thereon by the punch C.

Other modes of applying the principle of the invention may be employed, change being made

as regards the details described, provided the features stated in any of the following claims or the equivalent of such be employed.

I, therefore, particularly point out and distinctly claim as my invention:

1. Apparatus of the character described comprising, in combination, a support adapted to support a billet thereon at a predetermined level, clamping means for holding the billet against longitudinal movement with respect to said support, means including a part relatively movable in an axial direction with respect to said clamping means for forming an opening in an end of the billet, said clamping means having oppositely disposed parts movable toward each other into clamping engagement with the billet, said parts being operable upon movement into clamping engagement to move the billet into a position with its axis lying in a vertical plane containing the axis of said axially movable forming part, and means for adjusting said forming part with respect to said vertical plane to align its axis with the axis of the billet held by said clamping means, said adjusting means comprising a vertically movable support carrying said forming means, a horizontally movable support carrying said vertically movable support, a fixed support carrying said horizontally movable support, and means operable upon movement of said horizontally movable support relative to said fixed support to impart vertical movement to the support carrying said forming means.

2. Apparatus of the character described comprising, in combination, a support in the form of a conveyor adapted to move a billet longitudinally, an abutment adapted to retain the billet against such movement in one direction, clamping means adjacent to but independent of said abutment adapted to laterally engage the corresponding end-portion only of the billet and hold the billet against movement in either direction, and means for forming an opening centrally in such billet prior to drawing the latter into a seamless tube, said means including a punch movable in an axial direction with respect to such billet-end while held by said clamping means.

3. Apparatus of the character described comprising, in combination, a support in the form of a conveyor adapted to move a billet longitudinally, an abutment adapted to retain the billet against such movement in one direction, clamping means adjacent to but independent of said abutment adapted to laterally engage the corresponding end-portion only of the billet and an air hammer provided with a punch movable in an axial direction with respect to such billet-end while held by said clamping means.

4. Apparatus of the character described comprising, in combination, a support in the form of a conveyor adapted to move a billet longitudinally, an abutment adapted to retain the billet against such movement in one direction, clamping means adjacent said abutment adapted to engage the corresponding end-portion of the billet and hold the billet against movement in either direction, and means for forming an opening centrally in such billet end prior to drawing the billet into a seamless tube, said means including a punch movable in an axial direction with respect to such billet-end while held by said clamping means and said means being adjustable to align said punch with the center of such billet-end.

5. Apparatus of the character described com-

prising, in combination, a support in the form of a conveyor adapted to move a billet longitudinally, an abutment adapted to retain the billet against such movement in one direction, clamping means adjacent to but independent of said abutment adapted to laterally engage the corresponding end-portion only of the billet, and an air hammer provided with a punch movable in an axial direction with respect to such billet-end while held by said clamping means, said air hammer being bodily vertically adjustable to align said punch with the center of such billet-end.

6. Apparatus of the character described comprising, in combination, a support in the form of a conveyor adapted to move a billet longitudinally, an abutment adapted to retain the billet against such movement in one direction, clamping means adjacent said abutment adapted to engage the corresponding end-portion only of the billet and hold the billet against movement in either direction, said clamping means including replaceable jaws to fit billets of different diameters the lower engaging surfaces whereof lie in the plane of said billet support, and means for forming an opening centrally in such billet end prior to drawing the billet into a seamless tube, said means including a punch movable in an axial direction with respect to such billet-end while held by said clamping means.

7. Apparatus of the character described comprising, in combination, a support for a billet, clamping means adapted to laterally engage one end-portion only of the billet while resting on said support, said clamping means including replaceable jaws to fit billets of different diameters the lower engaging surfaces whereof lie in the plane of said billet support, and means for forming an opening centrally in such billet end prior to drawing the billet into a seamless tube, said means including a punch movable in an axial direction with respect to such billet-end while held by said clamping means.

8. Apparatus of the character described comprising, in combination, a conveyor adapted to receive a billet from a furnace and move the same longitudinally away therefrom, an abutment adapted to retain the billet against such movement in one direction, clamping means adjacent said abutment adapted to laterally engage the corresponding end-portion only of the billet and hold the billet against movement in either direction, means for forming an opening centrally in such billet end prior to drawing the billet into a seamless tube, said means including a punch movable in an axial direction with respect to such billet-end while held by said clamping means, and means adapted following the release of the billet from said clamping means to remove the billet transversely from said conveyor for transmission to a piercing mill or the like.

9. Apparatus of the character described comprising, in combination, a conveyor adapted to receive a billet from a furnace and move the same longitudinally away therefrom, an abutment limiting such movement, means adapted to engage the forward end of such billet and form an opening in such end while the billet is contacting such abutment and other means adapted following the release of the billet from said first-named means to remove such billet transversely from said conveyor for transmission to a piercing mill or the like.

RAYMOND E. DEWEY.
